UNITED STATES PATENT OFFICE.

HARRY G. DAVIS, OF PHILADELPHIA, PENNSYLVANIA.

AUTOMATIC TRAIN-CONTROL DEVICE.

Application filed September 21, 1914, Serial No. 862,754. Renewed July 21, 1922. Serial No. 576,650.

To all whom it may concern:

Be it known that I, HARRY G. DAVIS, citizen of the United States, residing at Philadelphia, in the county of Philadelphia and 5 State of Pennsylvania, have invented certain new and useful Improvements in Automatic Train-Control Devices, of which the following is a specification.

My invention relates to automatic train 10 control devices and particularly to means for making a service application of the air brakes when two trains approach within a predetermined distance of each other or when a train carrying a mechanism herein 15 described exceeds a prescribed rate of speed.

The object of the invention is to simplify 20 the structure as well as the means and mode of operation of train control devices whereby they will not only be cheapened in construction but will be more efficient in use, positive 25 in action, reliable and unlikely to get out of repair.

Many automatic train stopping devices 25 heretofore devised have contemplated the use of the emergency brake at each operation. The application of the emergency brake at frequent intervals or at times other than those of extreme necessity is unnecessary and highly objectionable.

One of the primary objects of this invention 30 is to provide means for automatically operating the engineer's brake valve to make a service application of the brake and thereafter to automatically return the engineer's 35 valve to the lap position.

A further object is to provide automatic means for regulating the degree of application 40 of the air brake in accordance with the speed of the train.

A further object of the invention is to so 45 connect the automatic operating mechanism and the engineer's brake valve and the throttle lever that said elements will be under the manual control of the engineer.

A further object of the invention is to provide 50 means for automatically closing the throttle valve of the engine simultaneously with the application of the brakes.

With the above primary and other incidental 55 objects in view, as will more fully appear in the specification, the invention consists of the features of construction, the parts and combinations thereof, and the mode of operation or their equivalents hereinafter described and set forth in the claims.

The invention forming the subject matter

hereof is applied in conjunction with air brake systems such as are now commonly in use. The use of the present invention does not necessitate any changes in the construction of the air brake mechanism or variation in the operation thereof. Such air brake system forms no part of the present invention and will not be shown nor described except so far as may be necessary for a complete disclosure of the invention. The invention has been shown and described in combination with parts of an air brake system of the Westinghouse type. It is to be understood however that the drawings are somewhat diagrammatic, no attempt having been made to show the air brake part and the control mechanism in their proper relative proportions.

Referring to the drawings, Fig. 1 is a side elevation of the assembled mechanism together with the related air brake parts, the throttle lever of the engine and the electrical control devices and connections, the latter being shown diagrammatically. In this figure the mechanism is shown in its normal or running condition. Fig. 1^a is a detail view of a modification or addition to the construction shown in Fig. 1. Fig. 2 is a plan view and Fig. 3 is an end elevation 85 of the automatic control mechanism, the latter being a view taken from the right of Fig. 2. Fig. 4 is a side elevation of the mechanism in a modified form, the parts being shown in the first stage of their operation by which the engineer's brake valve is shifted to service position, making a service application of the brakes, and by which the throttle valve is closed. Fig. 5 is a similar view of the mechanism illustrating the second stage of the operation thereof by which the engineer's brake valve is returned from service to lap position. Fig. 6 is a detail perspective view of the actuating bars in their normal or running positions. Fig. 7 is a detail plan view of the parts shown in Fig. 6. Fig. 8 is a detail plan view illustrating the interchangement of the operating parts preparatory to the second stage of operation by which the engineer's brake lever is shifted from service to lap position. Fig. 9 is a detail view of the reciprocating plate in its normal or running position. Fig. 10 is a similar detail view of the cam plate in its operated position. Fig. 11 is a diagrammatic view of the electrical circuits of two opposing trains upon the same track.

Fig. 12 is a diagrammatic view of a modification of the electrical circuits shown in Fig. 11.

Like parts are indicated by similar characters of reference throughout the several views.

The present system of train control embodies two electrical conductors arranged parallel with the track and a vibrating contact carried by each train, intermittently bridging the conductors and in the intervening intervals connecting electrically energized brake control members carried by the train into the conductor circuit. The electrical connections are such that as the vibrator moves in one direction, the electrically energized brake control members are bridged across the conductors, while upon the movement of the vibrator in the opposite direction such brake control members are excluded from the circuit and the conductors are connected directly one to the other.

The electrical capacity of the brake control members is such that if the conductors are bridged by an opposing train or otherwise, at a remote point during the interval that the control members are in the circuit, the resistance afforded by the intervening length of the conductors will prevent the operation of the brake control members. When the trains approach dangerously close one to the other upon the same track thereby reducing the resistance afforded by the intervening lengths of conductors, the brake operating devices will be energized by such bridging of the conductors, when the approaching trains are separated a predetermined distance.

No attempt is made to synchronize the vibrators of the separate trains but to the contrary, means are provided for operating the vibrator at irregular intervals which together with the variations in speed of the two trains will, in the course of a short cycle of operation, cause the vibrator of one train to bridge the conductors at the same time that the vibrator of the opposing train has brought its corresponding brake operating members into the circuit.

Each train set of mechanisms is complete within itself and is dependent upon an opposing mechanism only for the function of bridging the conductors. In order that the resistance of the conductors may be definitely proportioned to the distance at which the mechanism of the opposing train shall operate, additional resistance elements may be introduced into one or both the conductors, thereby causing the resistance of the conductors to decrease in definite steps as the opposing trains pass the resistance units.

The system is so arranged that when the circuit is closed through the brake operating devices, the air pressure is relieved, causing

application of the brakes. The system referred to is a closed circuit system, the circuits of which are protected by electrical devices so arranged that in the event of the breakage or interruption of the electric operating circuit such devices will automatically operate to apply the brakes.

Referring to the drawings, 1 is the engineer's brake valve of the Westinghouse type by which the air brake system is manually controlled. The control lever 2 of the brake valve is adjustable to five different operative positions, viz, releasing position I, running position II, lap or neutral position III, service position IV, and emergency position V. The engineer's brake valve 1 is connected with the main reservoir 3 by the pipe line 4. Connected with the engineer's brake valve 1 by a pipe line 5, is an equalizing reservoir 6. The main and equalizing reservoirs together with the engineer's brake valve are component parts of the ordinary air brake system. The throttle lever 7 is the ordinary lever by which the engine is controlled and is manually operated by the engineer in the usual manner. However in the present construction means, as herein-after described, are provided for automatically moving the throttle lever 7 to neutral or closed position, and for simultaneously automatically adjusting the engineer's brake valve to service position and subsequently returning it to lap position. Referring particularly to Fig. 1 which shows the assembled apparatus in its neutral or running condition, the operating parts of the apparatus are supported upon a main frame comprising a vertical wall plate 8 and a base 9. At one end of the main frame there is provided a vertical bearing sleeve 10 within which is journalled the shaft 11 of the governor 12. On the opposite end of the main frame is located a horizontal bearing sleeve 13 in which is slidably mounted a reciprocating operator slide bar 14. In a medial position upon the main frame intermediate the bearing sleeves 10 and 13 are vertical guides or ways 15 on which is mounted a reciprocating head 16 by which the actuator bars hereinafter described are moved into and out of operative positions.

The governor 12 is of the centrifugal type and is driven in any convenient manner from any suitable moving part of the engine. Either formed in the body of the governor shaft 11 or carried thereby, is a worm gear 18 driving a worm wheel 19 suitably journalled in the main frame.

Pivoted upon a bracket arm 20 projecting from the bearing sleeve 10 and engaging a crank pin 21 in the worm wheel 19, is an oscillatory slotted lever 22 to which are pivoted two reciprocating actuating bars 23 and 24. The actuator bars 23 and 24 are moved to and fro by the rotary movements

of the worm wheel 19. They are supported upon their forward ends by rollers or studs 25 carried by the head 16, and are capable of vertical adjustment about their pivotal 5 connections with the oscillatory lever 21 by the vertical movement of the head 16. The construction is such that the vertical adjustment of the head 16 will move the actuator bars 23 and 24 into and out of operative 10 position.

The actuator bar 23 is a pushing member, effective only in its forward movement or toward the left in the drawing, to shift the operator slide as hereinafter described. The 15 actuator bar 24 is hook shaped or provided with a lateral lug 26 whereby, upon its retrograde movement, it exerts a pulling action upon the slide 14 to retract the slide which has been previously advanced by the action 20 of the actuator bar 23. The operator slide 14 is provided with an offset or shoulder 27 on its upper face with which the extremity of the actuator bar 23 engages to advance the slide towards the left in Fig. 1.

The actuator bar 23 is capable of vertical movement independent of the second actuator bar 24 and independent of the head 16. The actuator 23 is normally held in an elevated position above the plane of the operator slide 14 by a reciprocatory plate 28 sliding vertically in suitable guides or keepers 29 of the main frame. The sliding plate 28 is actuated by means of a lever 30 pivoted upon the main frame and engaging the plate 35 28 at one extremity while at its opposite extremity it carries an armature 31 extending within the zone of influence of an electromagnet 32. When the magnet 32 is energized and the armature 31 is attracted thereby, the plate 28 is lowered, thereby permitting the actuator bar 23 to engage upon the operator slide 14.

It is to be understood that the actuator bars 23 and 24 are being continually reciprocated in unison with the rotation of the worm gear 19. Upon its succeeding forward movement, after being lowered into engagement with the operator slide, the actuator bar 23 will engage the shoulder 27 50 to advance the slide, toward the left in the drawing, to the position shown in Fig. 4. A spring detent 33 engages one of a series of notches in the face of the operator slide 14 to retain the slide in its adjusted position.

The operator slide is slotted throughout a portion of its length and within such slot there is pivoted a hook plate 34 having a shoulder 35 adapted to interengage with the hook or offset 26 of the actuator bar 24 when 55 the hook plate and actuator bar have been moved into operative positions. The reciprocatory plate 28 is provided with an inclined shoulder or cam surface 38 which engages an extension or finger 36 on the hook plate 34, as the plate 28 is moved upward to

retract the hook plate 34 against the tension of its spring 37. The shoulder 35 is thus normally held out of the path of the hook or lug 26 of the actuator 24. This is clearly shown in Figs. 6 and 9. Upon a downward movement of the sliding plate 28 the hook plate 34 is permitted to advance under the influence of its spring 37 as the cam face 38 is withdrawn from engagement with the extension or finger 36 until the shoulder 35 of 70 the hook plate 34 is projected beyond the face of the operator slide 14 into position to be engaged by the actuator bar 24 upon its retrograde movement.

The actuator bar 24 normally occupies a 80 position in a plane below that of the operator slide 14, as shown in Fig. 1, and is elevated into position to engage the shoulder 35 of the hook plate 34 by the upward movement of the sliding head 16. The actuator 85 bar 24 will engage the hook 35 of the hook plate 34 to retract the operator slide upon its next succeeding retrograde movement after having been elevated by the position of the head 16.

By its reciprocatory movement the operator slide 14 shifts a slide valve 39, with the stem 40 of which it is connected by a pivoted lever 41. The valve chamber 42 within which the slide valve 39 reciprocates, is connected by a pipe 43 with the main reservoir 3. The ports 44 and 45 which are opened and closed alternately by the sliding movement of the valve 39, communicate through corresponding pipes 44' and 45' with the 100 opposite ends of a cylinder 46. As shown in the drawings, the normal position of the slide valve 39 is such that both ports 44 and 45 are open to atmosphere through the usual exhaust outlet 39', and are closed against 105 the air pressure of the main reservoir which is communicated to the valve chamber 42 through the pipe line 43.

Located within the cylinder 46 is a reciprocating piston 47, the stem of which is 110 connected by a pitman 47' with a radially disposed oscillatory arm 2' connected to and movable in unison with the manual control lever 2 of the engineer's brake valve 1. Both ends of the cylinder 46 being normally 115 open to the atmosphere through the pipe lines 44' and 45' and the ports 44 and 45 and exhaust outlet, the engineer's brake valve is free for manual adjustment. During such manual adjustment the piston 47 120 will be reciprocated within the cylinder 46.

Located upon the side of the cylinder 46 are two air chambers 48 and 49 in each of which are mounted reciprocating plungers 50 and 51 respectively, adapted to be projected into the cylinder 46 against the tension of the retracting spring 52. The plunger 50 is so located that it will be projected into the path of the piston 47 to arrest it in its movement from running to service position. 130

The degree of movement permitted the piston by said plunger stop is such that the engineer's brake valve 1 is thereby adjusted to make a service application of the brake. 5 The second plunger 51 is so located that when projected into the path of the piston it will arrest the piston in its movement from service position at a point corresponding to the lap adjustment of the engineer's 10 brake valve.

The pipe 44' communicates with the air chamber 48 through a branch pipe 44" through which air is admitted to the chamber 48 to project the plunger 50 into the 15 path of the piston at the same time that the air is admitted into the cylinder 46 at the opposite side of the piston to drive such piston toward the operated plunger. A corresponding branch pipe line 45" connects the 20 pipe 45' with the second air chamber 49 and serves the same purpose of operating the plunger to arrest the piston simultaneously with the operation of the piston by the admission of air to the opposite side thereof. 25 Thus when the operating slide 14 is advanced by the action of the pushing actuator 23, the slide valve 39 is operated to uncover the port 44 thereby admitting air under pressure from the reservoir 3 through the pipes 44' 30 and 44" to move the piston 47 from running position as shown in Fig. 1, to service position shown in Fig. 4, where it is arrested by the protruding end of the stop plunger 50.

This movement of the piston is transmitted to the engineer's brake valve and serves to automatically shift the brake valve to service position IV. At the same time the air under pressure will pass from the pipe 44' through a branch pipe 53 to a cylinder 54 35 in which is mounted a reciprocatory piston 55. The piston 55 is connected by a pitman 56 with the catch lever 57 of the throttle lever 7 of the engine.

Under normal or running condition the 40 throttle lever 7 is free for manual operation in which case the piston 55 reciprocates within the cylinder 54 in unison therewith. However when the operator slide has been shifted, as before described, the air admitted to the cylinder 54 through the pipe 53 forces the piston 55 toward the right in Fig. 1. The initial movement of the piston 55 will serve to operate the catch lever 57 to disengage the catch from the notched segment 59 45 and the subsequent movement of the piston 55 under the influence of the air pressure will move the throttle lever to closed position as shown in Figs. 4 and 5.

The operation of the engineer's brake valve 60 1 to service position by the air pressure upon the piston 47 opens the pipe lines of the air brake system and relieves the pressure within the equalizing reservoir 6. The equalizing reservoir 6 communicates through a pipe 65 60 with a cylinder 61 in which is mounted

a reciprocatory piston 62 connected with the sliding head 16.

The piston 62 is normally held down against the tension of an elevating spring 63 by the air pressure within the cylinder 61 which corresponds with the pressure within the equalizing reservoir 6. When the air pressure within the equalizing reservoir is lowered by the operation of the engineer's 75 brake valve to service position, the pressure within the cylinder 61 is correspondingly lowered permitting the piston 62 to move upward under the influence of the spring 63 and thereby elevate the actuating bars 23 and 24 by the engagement of the rollers or 80 studs 25 therewith.

This upward movement of the head 16 under the influence of the spring 63 lifts the pushing or initial actuator 23 out of engagement with the operator slide 14 and elevates 85 the second or retracting actuator bar 24 into the plane of the operator slide. In its next retrograde movement the actuator bar 24 engages the shoulder 35 of the hook plate 34 to retract the operator slide 14 and thereby 90 shifts the slide valve 39 to open the port 44 to atmosphere through the exhaust 39' and to open the port 45 to the air pressure of the main reservoir which is communicated to the valve chamber 42 through the pipe 43. The 95 air under pressure then passes through the port 45 and the pipe 45' to the opposite end of the cylinder 46 and to the air chamber 49 causing the piston 47 to be moved toward the right in Fig. 1 from service position 100 where it is shown in Fig. 4 to lap position as shown in Fig. 5 and at the same time to cause the stop plunger 51 to be projected into the path of the piston to arrest it when it has reached lap position III, as shown in 105 Fig. 5, but does not change the position of the throttle lever.

To restore the parts to their normal positions after they have been operated by the retraction of the operator slide 14, there is 110 pivoted upon the main frame at 65, an oscillatory cam plate 66 actuated by a pull rod 69. The cam face 67 of the plate 66 engages a projecting stud 68 carried by the operator slide 14 to return the slide to normal position and thereby shift the slide valve 39 to its medial position. Thus both ports 44 and 45 are opened to the exhaust outlet thereby relieving the air pressure in both cylinders 115 46 and 54. This releases both the engineer's 120 brake valve 1 and the throttle lever 7 for manual operation.

In Fig. 1 there is shown a detent 70 adapted to engage a notch 71 in the pull rod 69 to retain the rod and cam plate in 125 their operated positions. The detent 70 is connected by a link 72 with a pivoted cam plate 73 with which a stud 74, carried by the throttle lever 7, co-operates. The arrangement of the cam plate and stud is such that 130

the detent 70 is permitted to drop into engagement with the pull rod only when the throttle lever is in closed position. The movement of the throttle lever 7 away from closed position causes the stud 74 to engage the inclined face of the pivoted cam plate 73 and thereby lift the detent 70 out of engagement with the pull rod 69 whereupon the rod and the cam plate 66 are retracted by the spring 75.

Thus the automatic mechanism may be locked in inoperative position so long as the throttle remains closed. However upon the initial movement of the throttle lever or control lever into operative position, the control mechanism is automatically unlocked.

It will be understood that the operation of restoring the automatic mechanism occurs before the air pressure in the equalizing chamber 6 and in the cylinder 61 has been restored to normal. The retracting actuator 24 at such time will be held in its elevated position in the path of the shoulder 35 of the hook plate 34 and would immediately re-engage the hook plate to return the operator slide if means were not provided to prevent such action.

To retract the hook plate 34 against the tension of its spring 37 to move the hook 30 or shoulder 35 out of the path of the retracting actuator bar 24 and thereby permit the operator slide 14 to be restored without interference with the actuator 24, there is provided in the guides or keepers 29 a second reciprocatory cam plate 76 identical in form and operation with the cam plate 28 but normally assuming a depressed position whereas the plate 28 is normally elevated. Pivoted upon the main frame at 77 is an actuating lever 78 engaged at one end with the sliding plate 76 whereby the plate will be elevated by the oscillation of the lever. Formed on the lower side of the lever 78 is a cam surface 79 engaged by a stud 80 carried by the oscillating cam plate 66. The construction is such that as the cam plate 66 is oscillated to restore the mechanism, the stud 80, acting upon the cam plate 79, elevates the lever 78 to correspondingly elevate the sliding cam plate 76. The cam plate 76 is provided with an inclined face corresponding with the inclined face of the cam plate 28 adapted to engage the finger or extension 36 of the hook plate 34 to press the hook plate out of the path of the actuator bar 24 against the tension of the spring 37.

In order that the application of the air brake may be made proportionate to the speed of the train, or, in other terms, in order that the degree of service application of the brakes may be extended through a greater or less period of time before the engineer's brake lever is returned to lap position in accordance with the degree of brake action necessary to arrest the momentum of

the train, it is necessary that the interval of time between the engagement of the pushing or initial actuator 23 with the operator slide 14 and the engagement of the retracting actuator 24 with the slide be varied. To this end the sliding head 16 is not connected directly or positively to the stem of the piston 62 but the construction is such that the piston 62 is permitted a greater or less initial movement in an upward direction before the head 16 is operated.

The sliding head 16 normally rests upon a stop 82 projecting from the guide ways 15 of the main frame and limiting the downward movement of the head 16. Attached to the lower end of the stem of the piston 62 is a supporting head 83 upon which is slidably mounted in suitable ways or guides, a reciprocatory wedge shaped or inclined member 84. The lower face of the sliding head 16 is inclined to correspond with the inclined face of the sliding member 84. The member 84 is connected by intermediate links 85 and 86 with the governor lever 87. The construction is such that the inclined member 84 is capable of simultaneous vertical and reciprocatory movement.

The governor lever 87 is pivoted to the frame arm 20 and engages the sliding collar of the governor, whereby, as the speed of the governor increases and the sliding collar is drawn upward against the tension of the governor spring, the governor lever 87 is oscillated to shift the inclined member 84 toward the left in Fig. 1 a distance proportionate to the speed of the train.

Upon the initial upward movement of the piston 62 under the influence of the spring 63 when the air pressure has been relieved, the head or support 83 is elevated in unison therewith, carrying the wedge shaped or inclined member 84 upward independent of the head 16, until the inclined member engages the lower inclined face of the sliding head 16 whereupon the sliding head 16 is moved in unison therewith. The degree of initial independent movement of the said parts will be dependent upon the relative position of the inclined member 84 upon the head 83. If the train and governor are being operated at a very high rate of speed the inclined member 84 will have been shifted toward the left in Fig. 1, as shown by dotted lines, and a movement of the head 83 and inclined member 84 of greater extent will be permitted before the sliding head 16 is engaged and moved therewith.

After the operator slide 14 has been advanced by the pushing actuator bar to make a service application of the brake, the operator slide will not be retracted to return the brake mechanism to lap position until the sliding head 16 has been elevated to correspondingly elevate the retracting actuator 24 into the plane of the operator slide 14.

- Therefore the intervening period of time during which the brake mechanism remains in service position, is dependent upon the relative position of the inclined member 84 at the time the service application is made. If the speed of the governor is very high and the member 84 is at the extreme limit of its stroke, a greater period of time will intervene before the inclined member engages and lifts the sliding head 16 than will intervene if the inclined member 84 is at the opposite limit of its stroke where it will normally be in contact with the inclined face of the head 16, as shown by solid lines in Fig. 1. Thus the period of service application is automatically proportioned in direct ratio to the speed of the train.
- The relative length of the period of operation may be varied by the adjustment of the screw threaded sleeve 64, thereby increasing or diminishing the tension of the spring 63. The position of the sleeve 64 in relation with a scale as in Fig. 4 indicates the tension of the spring and consequent period of brake operation.
- In Fig. 1^a is shown a feature which may be added to the construction shown in Fig. 1 to automatically render the apparatus inoperative when the engine is being housed. In this construction there is pivoted to the main frame a spring actuated lever 84' oscillated against the tension of its spring by the engagement of the stud 85' when the inclined member 84 is at the limit of its stroke toward the right in Fig. 1. Connected to the lever 84' is a reciprocatory cam bar 76', the inclined face of which engages and elevates the cam plate 76 when the inclined member 84 moves to its initial position. The plate 76 then holds the actuator 23 elevated, even though the brake magnet 32 may be energized. This device is optional and is not necessary to the successful operation of the apparatus.
- In order that the brake applying mechanism may be automatically operated to make a service application of the brake in the event that the electric controlling circuit is interrupted, broken, or becomes defective, there is provided in the controlling circuit a safety magnet 88, the armature 89 of which is carried upon a pivoted crank arm 90. The safety magnet 88 is of such electrical capacity and so connected that it will be normally energized, thereby holding its armature 89 in an elevated position. In event that the controlling circuit is broken the safety magnet 88 is demagnetized permitting its armature 89 to fall, thereby oscillating the pivoted crank 90 and causing the opposite arm thereof to engage a lug 91 upon the operator slide 14. The weight of the armature 89 is such that in falling it causes the operator slide 14 to be shifted by the engagement of the crank arm 90 with

the lug 91 to correspondingly shift the slide valve 39 to open the port 44 thereby making a service application of the brakes.

If means were not provided for rendering the retracting actuator inoperative in the event that the mechanism is operated by the release of the safety magnet, the retracting actuator 24 would, after the proper interval of time, tend to return the parts to lap position. By its retractive action upon the operator slide 14 it would cause the crank arm 90 and armature 89 to be thrown violently upward. The safety magnet 88, being demagnetized would not hold the armature in its elevated position. The armature would again drop only to be repeatedly elevated by the retracting actuator 24.

To prevent such action there is pivoted to the crank arm 90, a stem 92 which is adapted to engage the extended arm of the lever 78 when the crank arm 90 is depressed, thereby oscillating the lever 78 to elevate the sliding cam plate 76 independent of the action of the oscillatory cam plate 66, thereby retracting the hook plate 34 against the tension of its spring 37 to withdraw the shoulder 35 from the path of the retracting actuator 24.

To restore the armature 89 there is pivoted to the main frame a detent arm 93 adapted to engage a notch or shoulder 94 in the crank arm 90 to prop or support the crank arm and armature in their elevated position.

To oscillate the detent arm and the crank arm 90 upward into position to be engaged one with the other, there is pivotally connected to the oscillatory cam plate 66 a reciprocatory push rod 95 which engages the detent arm or prop 93. When the pull rod 69 is operated to restore the parts, the oscillation of the cam plate 66 elevates the push rod 95 thereby oscillating the detent arm or prop 93 which in turn bears upon and oscillates the crank arm 90 until engaged with the shoulder 94 thereof.

The length of the prop or detent arm 93 and location of the notch or shoulder 94 upon the crank arm 90 are such that the armature 89 will be supported within the zone of influence of the electromagnet 88 but not at the upper limit of the stroke of the crank arm 90 and the armature 89. The construction is such that when the electromagnet 88 is reenergized it will lift the armature 89 from its supported position, thereby disengaging the notch or shoulder 94 from engagement with the prop or detent arm 93 whereupon the detent arm will fall by gravity to the position shown in solid lines.

Pivoted supported upon the frame arm 20 is an oscillatory arm 96 carrying the vibrating contact 97 before mentioned. The arm 96 is oscillated to and fro under the control of an irregular cam 99 for convenience

shown as carried upon the shaft of the worm gear 19 and rotating in unison therewith and engaged by a roller 98 carried by said arm. The oscillating arm 96 is actuated by the 5 cam 99 against the tension of a retracting spring 100 at irregular intervals. It is to be noted that the cam 99 is provided with cam faces of unequal extent and unevenly spaced to produce an irregular operation of the 10 vibrator arm.

The vibrating contact 97 is electrically connected with the conductor *a*, through a sliding contact shoe *a'*. When oscillated in one direction under the influence of the 15 retracting spring 100 it engages with a contact 101 electrically connected with the brake control magnet 32. When oscillated in the opposite direction by the action of the cam 99 against the tension of the spring 100, the 20 vibrating contact 97 engages with a contact 102 which is electrically connected with the second conductor *b* through a sliding shoe *b'*.

The contact 102 is preferably yieldingly 25 supported upon a pivoted arm 103 which is capable of yielding against the tension of the spring 104. By this construction the retracting spring 100 will compensate for any 30 irregularity in the adjustment of the contacts 101 and 97 or the wear of the contact points while the spring 104 will compensate for similar lack of adjustment or wear upon the contacts 102 and 97.

The construction shown in Figs. 4 and 5 35 differs from that shown in Fig. 1 and heretofore described in that the governor and its operating connections are omitted. In the construction shown in Figs. 4 and 5 the worm gear 19 is driven by a worm 106, the 40 shaft of which may be connected with any operating portion of the engine but which is preferably the extremity of the generator shaft by which current is generated for the 45 operation of electromagnets forming parts of the apparatus. This generator may be driven in any well known manner from the moving engine parts but is preferably operated by means of a steam turbine of suitable size supplied from the engine boiler. The cam 50 99 is preferably continuously operated independently of the travel of the engine. By the use of the steam turbine the mechanism will be continued in operative condition during such intervals of time that the engine 55 remains at rest. In this form of device the oscillated slotted lever 22 and the vibrator arm 96 are pivoted to the base of the main frame in lieu of the frame arm 20. The cam 99, in this form of device, is connected with 60 the gear 19.

The governor having been omitted from this form of construction, there is no means for regulating the apparatus to proportion the interval of time between the service application of the brake and the return of the 65

brake mechanism to lap position in relation to the speed of the train. Therefore in the construction shown in Figs. 4 and 5 the stem of the piston 62 is connected directly to the sliding head 107, corresponding to the sliding head 16 of the previously described construction. This sliding head 107 operates in the same manner and performs the same functions as the sliding head 16 of the construction shown in Fig. 1.

The contacts 101 and 102 are shown in inverted positions in Figs. 4 and 5 and the cylinder 46 of the brake valve operating mechanism is shown integral with the valve chamber 42, the sliding valve 39 of which is connected directly to the operator slide 14. With the exception of these changes in the construction, which do not in any way alter or modify the operations of the mechanism, the construction and operation of the apparatus shown in Figs. 4 and 5 are the same as that shown in Fig. 1 and previously described.

Referring again to Fig. 1 and to the diagrammatic view Fig. 11, *a* and *b* are the conductors arranged parallel with the track and engaged by the sliding contact shoes *a'* and *b'* carried by the train. Located at spaced intervals in one or both conductors, are resistance units *c* whereby the resistance of the conductors will be increased or diminished to a material degree and preferably in definite steps in proportion to the length of conductor under consideration.

Current is supplied for the operation of the electrical devices by a generator *d*, one side of which is electrically connected through the line 108 with the sliding contact shoe *b'*. The opposite side of the generator *d* is connected through the line 109 with the 100 brake magnet 32 and then through the signal magnet 134 and the line 110 with the contact 101. As before stated, the vibrating contact 97 is electrically connected through the line 111 with the sliding contact shoe *a'*.

When the vibrating contact 97 engages the contact 101 the brake operating magnet 32 and generator *d* are bridged across the conductors *a* and *b*. If at the same moment the vibrator 97 of the opposing train mechanism *Z* engages its corresponding contact 102 which is electrically connected with the sliding shoe *b'* through the line 112 which bridges the conductors *a* and *b* or connects them directly one to the other, the operating circuit will be completed. Under such conditions the current flowing through the completed circuit is insufficient to excite the brake magnet 32 to cause it to attract its armature while the trains are at a safe distance apart. However if the trains are within the prescribed operating range or danger zone the brake mechanism of the initial train set *X* will be operated by the current passing from the generator *d* through the line 113

109 to the brake magnet 32, then through the signal magnet 134 and the line 110 to the contact 101 and to the vibrating contact 97 engaged therewith and then through the 5 line 111 to the sliding brake shoe a' of the initial train set indicated at X in Fig. 11, and then through the conductor a to the brake shoe a' of the second train set Z and through the line 111, the vibrating contact 10 97, which in the second train set Z is engaged with the contact 102 at that particular moment, and then through the line 112 to the sliding contact shoe b' of the second train set Z and then through the 15 conductor b back to the sliding contact shoe b' of the initial train set X from which it returns to the generator through the line 108. Thus a shunt circuit is closed around the safety magnet 88 in which shunt is included the brake operating mechanism of the 20 initial train set X. This shunt circuit is closed by the action of the second train set Z. It is to be noted that there is provided a normally and constantly closed local circuit extending from the generator d through the line 109 to the brake magnet 32, thence through the signal magnet 134, thence through the safety magnet 88, thence returning through the line 130 to the contact 25 shoe b' , thence through the line 108 to the negative side of the generator. This closed circuit supplies sufficient current at all times to enable the safety magnet 88 to hold the lever 90 in elevated position. Should 30 any accident occur whereby this circuit is broken or the generator disabled, the safety magnet 88 will of course release the elevated lever 90 the falling of which sets the mechanism into operation as before described. 35 This, however, is only an emergency or safety device. Under normal operations, the current passing through this succession of magnets including the safety magnet is insufficient to effect the operation of the 40 brake magnet 32. However, when the shunt above described is closed whereby a portion of the current will be passed through the line 110 and the conductor a to the opposite train set and returned to the conductor b and line 108 to the opposite side of the generator without passing through the safety magnet 88 the current becomes 45 sufficient to energize the brake magnet 32. It will be understood however that sufficient current will continue to pass through the safety magnet 88 to enable it to hold the arm 90 in elevated position. In other words, the brake magnet 32 cannot be operated through said safety magnet but is operated 50 by bridging the main or normally closed circuit before referred to to close the circuit independent of the magnet 88. This action of the brake magnet 32 may not immediately occur if the trains are widely separated. 55 Under certain conditions the resistance af-

fording by the length of the conductors a and b and the included resistance c in said conductors may temporarily prevent the operation of the brake magnet 32.

If the second train set Z is at a remote 70 distance sufficient to afford a reasonable degree of safety, the resistance of the conductors a and b together with the intervening resistance units c will be sufficient to prevent the operation of the electromagnet 75 32 until the trains X and Z approach into dangerously close proximity one to the other. In such event the elimination of a portion of the resistance intervening between the two trains will permit the passage of sufficient current to cause the brake magnet 32 to lift its armature and thereby operate the mechanism in the manner before described. 80

It will be understood that the vibrating contacts 97 of both trains are in constant 85 operation. The contact 97 of the train Z, having bridged the conductors to close the operating circuit through the operating mechanism of the train set X, as just described, the contact 97 of the train set X 90 will then, in the course of its operation, engage the contact 102 to bridge the conductors a and b at a time when the contacts of the second train set Z are so engaged as to include the operating magnet 95 32 of the second train set Z in the circuit, whereupon the mechanism of said second set will be operated. Thus the mechanisms of both trains will be automatically operated to apply the air brakes when the trains approach within a dangerously close distance. In addition to the means of control before described, means is provided by which the same apparatus may be employed to reduce the speed of the trains to a predetermined 100 rate at certain points in the track.

The limit of speed at which the train may safely operate at such points having been previously determined, ramp rails 114, Fig. 1, are located between the track rails 110 115 in definite relation therewith. These ramp rails are so located as to be engaged by a corresponding contact operating member 116 carried by the train. At the bottom of Fig. 1 there has been shown a cross 115 section of the track with a series of ramp rails located therein in positions corresponding to maximum speed of 20, 40, and 60 miles. It is to be understood that these figures are merely arbitrary and that other 120 rates of speed may be adopted. It is to be further understood that while three ramp rails 114 are shown in Fig. 1 that in actual practice only one such rail will be used at a given point, the said rail being 125 so positioned as to engage the contact operating member corresponding to the maximum safe speed permitted at that point.

Slidably mounted in suitable guide or frame 117 located upon the main frame of 130

- the apparatus, is a reciprocating head 118 connected with the governor lever 87 by the link 86 and moving in unison therewith. Thus the degree of movement of the head 118 is dependent on the operation of the governor 12. Carried by the sliding head 118 is a contact finger 119. This finger 119 slidingly engages a contact bar 120 located upon the main frame and as the head 118 advances the finger 119 engages successively a series of contact bars 121 of different lengths, thereby electrically connecting said contact bars 121 with the primary contact bar 120. The contact bars 121 are so proportioned and relatively located that the contact finger 119 will engage each succeeding bar only when the train has attained a corresponding rate of speed.
- The primary contact bar 120 is electrically connected through the line 122 with one side of the generator d . The contact bars 121, each of which corresponds with a different maximum speed and which are correlated with the ramp rails 114, are connected through lines 123 with contacts 124 corresponding with said contact bars 121 and ramp rails 114. The opposite sides of each of the contacts 124 are connected through a line 125 with the brake magnet 32 which in turn is connected through the line 109 with the opposite side of the generator.
- When the train is operating at a low rate of speed the contact finger 119 will engage only the primary contact bar 120 and the circuit will be broken intermediate the contact finger 119 and the contact bars 121. As the speed increases the sliding head 118 is operated toward the left in Fig. 1 by the action of the governor lever 87, thereby carrying the contact finger 119 into engagement with the longest contact bar 121 which in the present instance is assumed to correspond with the maximum speed of 20 miles per hour. As the speed increases beyond this maximum the contact finger 119 is shifted to successively engage the medial contact bar 121 which is assumed to correspond with the rate of speed of 40 miles per hour and finally to engage the short contact bar 121 which is assumed to correspond with the rate of speed of 60 miles per hour.
- If while the contact finger 119 is engaged with contact bars 121 a ramp rail 114, located to engage the switch operator corresponding to the maximum rate of 20 miles per hour, such ramp rail 114 will cause the contact operator 116 to close the corresponding contact 124 thereby closing the circuit from the generator d through the line 122 to the primary contact bar 120 then through the contact finger 119 to the contact bars 121 engaged by the finger 119, then through the line 123 to the correspond-
- ing switch 124 and through the line 125 to the electromagnet 32 which is connected through the line 109 with the generator. The closing of the shunt circuit as traced causes the electromagnet 32 to lift its armature to operate the mechanism in the manner before described. The brake is thus applied to a degree and for an interval of time determined by the position of the inclined member 84, which in turn is regulated by the governor, to reduce the speed of the train to a rate less than 20 miles per hour.
- If, however, while running at a rate of less than 40 miles per hour, a ramp rail corresponding to a maximum speed of 40 or 60 miles an hour is encountered, such ramp rail would cause the closing of the corresponding contact 124 but such action would be ineffective since the contact finger 119 will not have made engagement with the corresponding contact bar 121 at such rate of speed. Thus the mechanism is not operated unless the train is exceeding the prescribed rate of speed. In the event that the train is exceeding the prescribed rate of speed the ramp rail 114 located in the track in position to engage the contact operator corresponding to the prescribed speed limit will close the contact 124 to cause the operation of the brake mechanism.
- It will be understood that the irregular cam 99 is rotated continuously regardless of whether the train is standing still or is running at either a high or a low rate of speed. This is accomplished by an independent driving motor or by operating it in unison with the generator which is preferably operated by a steam turbine. The driving motor may be belted to a pulley 133 connected to the cam. The vibratory arm 96 and the contact 97 will therefore be in continual operation alternating the engagement of the contact 97 with the contacts 101 and 102. Such engagement therefore will be of only momentary duration. If the engagement made with the contact 101 to close the circuit momentarily through the brake operating magnet 32, occurs at the moment that the pushing actuator 23 is in position to engage with the sliding operator bar 14, the brake operating mechanism would be subsequently operated. If, however, the brake magnet 32 was only momentarily energized during the retrograde movement of the actuator bar 23 or when such bar is at the rearward limit of its stroke, and cooperating means were not provided to insure the operation of the brake mechanism, the brake magnet 32 might be de-energized and thereby release its armature, and elevate the slide 28 and the actuator 23 before the actuator could have performed its function of advancing the operator slide 14. To insure the operative engagement of the actuator 130

bar 23 and the sliding operator 14 for a sufficient length of time to complete their operative movements, there is provided a detent 126 which engages the sliding plate 28 to hold the plate in its lowermost position when lowered by the attraction of the armature 31 of the magnet 32. This detent 126 holds the plate 28 in its depressed position and the armature 31 in its elevated position until released by the subsequent manual restoring operation. Thus the pushing actuator 23 is permitted to ride upon the sliding operator bar 14 until lifted therefrom by the upward movement of the sliding head 16 of the Fig. 1 construction or the sliding head 107 of the Fig. 4 construction under the influence of the piston 62 actuated by the spring 63. The pivoted detent 126 is provided with a cam arm 127 resting upon a stud 128 carried by the operating arm of the cam 66. The construction is such that upon the oscillation of the cam 66 during the restoring operation, the stud 128 will elevate the cam arm 127 to oscillate the detent 126 out of engagement with the sliding plate 28. The plate, being thus released, returns to its elevated position under the influence of the falling armature 31 which is operated either by gravity or by means of a suitable retracting spring.

In the circuit diagram of the opposition train Z, in Fig. 11, there is shown electrical means for accomplishing the same result. This consists of a shunt circuit 129 adapted to be closed by the attraction of the armature 31. Thus when the magnet 32 is momentarily energized by the engagement of the contact 97 with the contact 101 and thereby momentarily attracts the armature 31, it closes the shunt circuit through the magnet 32 and the line 129 to the opposite side of the generator thereby continuing the flow of current through the magnet 32 after the contact has been broken between the contacts 97 and 101. The armature 31 thus being held in its elevated position, will maintain the sliding plate 28 in depressed position thereby permitting the continuous operation of the sliding head as before mentioned. In this construction the armature may be restored and the shunt circuit broken manually as is the detent 126 of the mechanical construction.

Referring to the wiring diagram of the train X in Fig. 11 it will be seen that the safety magnet 88 is contained in a circuit common with the signal magnet and with the brake magnet 32. This circuit extends from the generator through the line 109 to the brake magnet 32 then through the connector to the signal magnet 134 and through the second connector to the safety magnet 88 then through the line 130 which might be connected to the opposite side of the generator but which instead is carried to the shoe

b' from which the circuit is completed to the generator through the line 108. This makes the connecting line 108 a part of the circuit. If the line 108 should be broken the safety magnet will be demagnetized thereby causing the operation of the brake operating mechanism. The same result would occur if the generator should be disconnected or if wiring becomes disarranged or if any brake occurs in either of the magnets or in their intermediate connections. Thus, not only the magnets and their connections to the generator are protected but also the line 108 between the generator and the sliding shoe b'. It will be noted, however, in the wiring diagram of the train X in Fig. 11 that the lines 110, 111 and 112 are unprotected. That is, if either one or all of these lines 110, 111 and 112 should be broken, the safety circuit would not be interrupted and therefore the safety magnet 88 would not operate to cause the application of the brakes. Referring now to the wiring circuit of the train Z in Fig. 11, it will be noted that the line 130 from the safety magnet 88 is connected to the contact 102 whereby such safety circuit will include not only the line 108 of the sliding contact shoe b' to the generator but also the connecting line 112 intermediate the contact 102 and the sliding contact shoe b'. This will fully protect the line 112 whereby if such line is broken, the safety circuit is interrupted and the magnet 88 de-energized thereby causing an application of the brakes. To protect the line 110 the safety magnet 88, instead of becoming connected directly with the brake magnet through the signal magnet, is connected through a line 131 with the contact 101 which in turn is connected through the line 110 with the signal magnet and brake magnet, and thence to the generator. By this form of wiring, the line 110 is made a portion of the safety circuit whereby if such line should be broken the safety circuit would be interrupted and the magnet 88 de-energized to cause an application of the brakes. Thus in the diagram of the wiring of train Z, the lines 110 and 112 together with the line 108 are fully protected by the safety magnet. In this form of wiring the line 111 is the only point in the operating circuit which has not been afforded ample protection.

In Fig. 1 the signal device has been shown as a bell. In Fig. 11 there is shown a signal magnet 134 which when energized closes a signal light circuit 132. It is to be understood that the signal magnet and the brake magnet are so wound as to respond under the influence of current of different voltage or the armatures 31 of the magnet 32 and armature 146 of the magnet 134 are differently tensioned whereby the signal magnet will operate at appreciable interval of time in

advance of the brake magnet. The brake magnet and the signal magnet are so proportioned in relation one with the other, that the signal magnet will be operated by a current of much lower voltage whereby it will operate to energize the signal lamp, the bell, or whatever signal means may be employed when the trains are separated a distance substantially twice the distance at which the 5 brake magnet is operated. When, as shown in Fig. 11, the brake magnet 32 is operated through several rail sections and two intervening resistance units *c* but is not operated through three of such resistance units the 10 signal mechanism will be proportioned to operate through four or more of such resistance units. This signal operating feature is fully set forth and described in the 15 prior application of George L. Campbell before referred to.

In the protective wiring system shown in Fig. 12 there are employed in addition to the 20 brake magnet, the signal magnet and the safety magnet, before mentioned and described, a main line cut out magnet 135 controlling a make and break contact in the main line and two auxiliary cut out magnets 136 and 137 having an armature 138 common to both magnets controlling a make and 25 break contact in the protective circuit.

It will be noted that in this form of wiring the main line cut out magnet 135 and the safety magnet 88 are both compounded or double wound. The object in compounding 30 the safety magnet 88 is to afford a greater margin of safety by causing it not to release its armature unless some part of the circuit is broken or opened, thereby effecting a drop in potential. In the wiring construction shown in Fig. 11, when the operating 35 circuit is closed through the brake magnet by the approach of a second train, the increased load due to the connection of the rails *a* and *b* by the mechanism on the train 40 in advance causes the generator voltage to drop. Under such condition fine and accurate adjustment is necessary to enable 45 the single wound safety magnet 88 to hold its armature. By compounding this magnet, however, the pulling influence upon 50 the safety armature by the magnet 88 will be much greater when the drop in voltage, due to the operation of the brake magnet 32, takes place. Under such compounding 55 of the windings of magnet 88, the interconnection of the rails *a* and *b* by the advance train shunts the lower coil of the magnet 88 through the external circuit which results 60 in an increased flow of current through 135, 32, 134 and the upper winding of magnet 88.

The cutout magnet 135 embodies one winding connected with the line 139 to the generator and connected at its opposite side to the armature of the cutout magnet and 65 thence through the contact 140 to the brake

magnet 32 and thence through the signal magnet 134 and through one winding of the safety magnet 88, etc. The second winding of the compound cutout magnet is connected in the shunt circuit 152 extending from the 70 line 139 through the second winding of the cutout magnet to the line 144' with which it connects to the opposite side of the generator. The second winding of the safety magnet is in a circuit which includes the line 142, 75 143, the armature 138 and line 144'. The compounding of the safety magnet 88 affords a greater factor of safety or more latitude in the construction and operation of the device. It is not necessary that the 80 magnet should be wound and adjusted with as great accuracy when compounded as when single.

The drop in voltage due to increased loading of an ordinary shunt wound generator, 85 upon approach of two trains, is so great that for best results compound wound generators are employed. Without the use of the cut-out magnet 135, the current from the generator having the highest voltage 90 would flow back through the safety magnet 88, signal magnet 134, brake magnet 32, and series field of the opposing generator of lowered voltage, resulting in a reversal 95 of polarity thereof. However, this is overcome by the introduction of the cut-out magnet 135 which under such condition would drop its armature and momentarily open the circuit, preventing the current traversing the series field of the lower 100 voltage generator, and causing a reversal 105 of polarity. The released armature of the cut-out magnet will be immediately retracted and the contact 140 again closed by current from the positive side of the generator through line 152 and shunt winding of coil 135 thence through 152 and 144' to the negative side of the generator. If shunt wound dynamos are employed, under 110 such condition the low voltage generator 110 would merely be actuated as a motor and no reversal of polarity would occur.

In tracing the circuits, starting at the positive side of the generator, the current passes through the line 139 to the cut out 115 magnet 135, thence to the armature thereof, which normally holds the main line closed, through contact 140 thence in succession through the brake magnet 32, the signal magnet 134, and the safety magnet 120 88, which operates to apply the brake only when the circuit is broken, thence through the line 141 to the contact 101, returning to the shunt winding of the safety magnet 88 through the line 142 thence through the 125 line 143 through the contact 144 controlled by the common armature 138 of the protective magnets 133 and 137 thence through the line 144' to the negative side of the generator.

A shunt circuit 145 from the positive side of the generator leads to the contact 146 controlled by the armature of the signal magnet and thence through the line 147 5 to the protective magnet 136 and then through the line 148 to the vibratory contact 97; thence through the line 111 to the shoe *a'* from which it passes through the line 149 to the second protective magnet 10 137 and then through the line 150 to the contact 102, through the line 112 to the shoe *b'* and returns through the line 108 to the negative side of the generator. 15

It will be noted that every circuit is thus protected except the short line between the armature of the signal magnet and the line 143 in which is included the signal lamp 153. This is unimportant as the 20 brake operating mechanism will operate whether the signal lamp has been previously energized or not.

Thus if any line of the system before traced should break, the safety magnet 88 will be de-energized thereby permitting the 25 arm 90 to fall and by its action setting the brake mechanism in operation. The generator being started, the shunt winding of the main line cut out magnet 135 is energized by current through the line 152 from 30 the line 139 to the negative side of the generator. The cut out magnet being energized, attracts its armature and thereby closes the main circuit at the contact 140 through the series windings of the cut out 35 magnet, the brake magnet, the signal magnet, and the safety magnet and then to the contact 101 thence back through the line 142 to the second winding of the safety magnet thence through the line 143 40 to the armature 138, through the contact 144 and the line 144' to the negative side of the generator. This completes the local circuit which keeps the safety magnet 88 sufficiently energized to retain its 45 armature and the arm 90 in elevated position. If the contact 101 and the contact 97 are in engagement, and the contact rails *a* and *b* are bridged within the prescribed distance, a shunt circuit is established 50 through the line 111 from the contact 97 to the shoe *a'* and contact rail *a*, and thence through the bridge established by the opposition train or otherwise to the contact rail *b*, thence through the intervening resistance 55 *c* to the shoe *b'* and the line 108 to the negative side of the generator. If there is no opposition train and no other bridging of the conductors *a* and *b* occurs within a dangerous distance no action will result due 60 to the resistance offered by the great extent of the conductors *a* and *b* and interposed resistance *c*. If however the shunt circuit is closed within the prescribed distance sufficient current will pass through 65 such bridge to the opposite shoe *b'* and

then through the line 108 to the opposite side of the generator, to operate the signal magnet which will thereupon attract its armature, closing contact 146 to energize the signal lamp 153. The signal lamp 153 70 is energized through the line 145 from the positive side of the generator through the contact 146, the armature of the signal magnet and then through the lamp to the line 143 then through the contact 144, controlled by the armature 138 of the protective magnets 136 and 137, and then through line 144' to the negative side of the generator. A small amount of current flows from the positive side of the generator 80 through the line 145 to the contact 146 and then without passing said contact 146, through the line 147 to the protective magnet 136 then through the vibrating contact 97 and the shoe *a'* back to the second 85 protective magnet 137 then through the contact 102 and shoe *b'* to the negative side of the generator. This is strictly a protective circuit and is normally closed. It serves to protect the shoes and the operating circuit. If any of the lines or shoes should be broken, the armature 138 will be released thereby opening the circuit through the safety magnet 88.

Assuming now that the contacts 97 and 95 102 are in engagement one with the other, the current flows from the positive side of the generator through the lines 145 and 147 to the coil 136 thence through line 148 to the vibrating contact 97 and through the 100 contact 102, line 112 to the shoe *b'* and thence through the line 108 to the negative side of the generator. It will be seen that the protective magnet 137 has been thus shunted. It is to be understood, however, 105 that the magnets 136 and 137 are of high resistance and so long as the circuit is closed through one of them the other coil may be shunted without effect and the armature 138 will be maintained in normal position. However, if, both magnets 136 and 137 were shunted at the same time the armature 138 of course would be released. Thus either one of the protective magnets 136 and 137 is sufficient to maintain the safety 110 magnet 88 in a closed circuit independent of the other protective magnet. When the contacts 97 and 101 are in engagement, the protective magnet 136 will be shunted or bridged, the current passing from the positive side of the generator through the line 139, the upper winding of magnet 135, magnets 32 and 134 and upper part of magnet 88, and line 141, as before stated, to the contact 101 where it meets a very light 115 current from the magnet 136 through the line 148 to the contact 97. The magnet 136 being of high resistance is bridged by said series of magnets of lower resistance. From the contacts 97 and 101 the current con- 120

125

130

tinues through the line 111 to the shoe α' then through the line 149 to the magnet 137 then through the line 150, the contact 102, line 112 and line 108 to the opposite 5 side of the generator. In this circuit the protective magnet 136 has been shunted. There are thus in reality two paths for current from the generator to contact 101, a high resistance circuit through the magnet 136, and a low resistance circuit through the series of cut-out, brake, signal and safety magnets which being the predominating course bridges the magnet 136 rendering it inoperative. Thus the protective magnets 10 136 and 137 are alternately short circuited but at no time do they simultaneously release their armature 138 unless the circuit 15 should be accidentally opened by the breakage of some one of the lines.

20 While there has been shown for illustrative purposes an ordinary form of centrifugal gravity governor, it is to be understood that the invention is not in any sense limited thereto, but for practical operation, a governor not affected by vibration or jar, as fluid governors, spring governors, inertia governors, or like control means will be found most desirable.

There is thus provided a constantly closed 30 circuit system controlling the brake operating mechanism which is adapted to cause the application of the brake in the event that the controlling circuit is accidentally opened or in the event that an opposing train approaches within dangerous proximity and thereby closes a shunt circuit between two branches of the protected circuit. The coil or magnet 88 which is located in the constantly closed local circuit affords such a degree of resistance or in other words consumes so much current that the current passing through this closed circuit is not sufficient to energize the brake magnet or relay 35 32 sufficiently to cause it to attract its armature 31 so long as the resistance afforded by the safety magnet 88 is included in the circuit. Normally the brake magnet 32 and the safety magnet 88 are connected in series. However by the closing of the shunt circuit 40 by the action of the distant train, the safety magnet 88 and the brake magnet 32 are connected in multiple thereby enabling the operation of the brake magnet 32 while the safety magnet 88 will still continue to receive sufficient current to enable it to hold 45 its armature and the arm 90 in elevated positions.

In automatic brake operating mechanism heretofore commonly employed it has been 60 customary to cause the automatic mechanism to make an emergency application of the brake. In the present instance the automatic means operates the brake in exactly the same manner that the engineer would 65 do so by manual effort. Instead of an emer-

gency application the engineer's control valve is operated to a service application and is automatically returned thence to lap position. The interval of time between the service application and the return to lap position is determined by the speed of the train. 70

From the above description it will be apparent that there is thus provided a device of the character described, possessing the 75 particular features of advantage before enumerated as desirable but which obviously is susceptible of modification in its form, proportion, detail construction or arrangement of parts, without departing from the 80 principle involved or sacrificing any of its advantages.

While in order to comply with the statute, the invention has been described in language more or less specific as to certain 85 structural features, it is to be understood that the invention is not limited to any specific details, but that the means and construction herein described comprise but one mode of putting the invention into effect, 90 and the invention is therefore claimed broadly in any of its possible forms or modifications within the scope of the appended claims.

Having thus described my invention, I 95 claim:

1. In a vehicle control mechanism, a brake, a control member therefor, capable of movement to different relative positions, an actuator for automatically actuating said 100 control member movable initially in one direction, and upon reaching the limit of the initial stroke automatically reversing the movement thereof through a retrograde movement of less extent than such initial 105 movement.

2. In a vehicle control mechanism, the combination with an air brake system including an engineer's control valve therefor, of means for automatically operating the 110 control valve to effect a service application of the brake and thereafter return the control valve to neutral or lap position, comprising a cylinder, a piston therein, actuating connections between the piston and control valve, means for admitting air under pressure to said cylinder initially at one side of the piston and subsequently at the opposite side of the piston to move said piston alternately in opposite directions, and means to automatically limit the movement of the piston in either direction to a range 115 of travel less than the full stroke of which the piston is otherwise capable.

3. In a vehicle control mechanism, a control member capable of movement to different relative positions, a brake controlled thereby, means for automatically actuating said control member, to apply said brake, and means to automatically effect the sub- 125 130

sequent return of said control member to neutral position and regulating means for automatically determining the intervening interval of time between the initial operation of said control member and its return to neutral.

4. In a vehicle control mechanism, a brake, a movable brake control member, a control lever for the vehicle, and fluid pressure means for initially operating the brake control member and the vehicle control lever simultaneously and thereafter automatically returning the brake control member to neutral position independent of the vehicle control lever.

5. In a vehicle control mechanism, a fluid pressure reservoir, a brake, a brake control member, a control lever for the vehicle, independent actuating means for vehicle control lever and brake control member for automatically operating the vehicle control lever to neutral position simultaneously with the movement of the brake control member to apply the brake, means for automatically returning the brake control member to neutral position independent of the actuating means for the vehicle control lever.

6. In a vehicle control mechanism, a fluid pressure reservoir, a brake, a brake control member, a cylinder, a piston therein connected with the brake control member and actuated by fluid pressure from the reservoir, and fluid pressure operated stops to arrest the movement of the brake control member in either direction.

7. In a vehicle control mechanism, a throttle lever, means for automatically actuating the throttle lever, and electrical control means therefor including a normally closed circuit, and electrically operated member in said circuit, electrical resistance also in said circuit normally preventing the operation of the said electrically operated members, and a shunt circuit adapted to be closed by an independent distant vehicle to eliminate the influence of said electrical resistance and thereby permit the operation of said electrically operated member.

8. In a vehicle control mechanism, a brake, automatic operating means therefor, and electrical control means therefor including a normally closed circuit, an electrically operated member in said circuit, electrical resistance in said circuit normally preventing the operation of the said electrically operated member, and a shunt circuit adapted to be closed by a distant vehicle to eliminate the influence of said electrical resistance and thereby permit the operation of said electrically operated member.

9. In a vehicle control mechanism, a brake, brake actuating means, a control member for the vehicle motive power, automatic actuating means for said control member, electrical governing means for the brake

actuating and control member actuating means including a normally closed circuit, an electrically operated member in said circuit, electrical resistance also in said circuit normally preventing the operation of said electrically operated members, and a shunt circuit adapted to be closed by a distant vehicle to eliminate the influence of said electrical resistance and thereby permit the operation of said electrically operated member.

10. In a vehicle control mechanism, a control member, means for automatically actuating the control member, track positioned means for initiating the operation of the actuating mechanism operative at certain predetermined speeds of the vehicle and inoperative at other speeds thereof, said actuating means being held in operative position solely by said track positioned means and permitted to return to condition preparatory to the next operation, immediately upon the passage of the track positioned means.

11. In a vehicle control mechanism, a brake, a brake control member, a control member for the vehicle motive power, means controlled from a distant point for simultaneously operating both control members, and automatic means for subsequently reversing the brake control member independent of the control member of the vehicle motive power.

12. In an apparatus of the character described the combination with an air brake mechanism capable of adjustment to "running" "service" and "lap" positions, of fluid pressure operated means to automatically adjust said air brake mechanism from "running" position to "service" position and thence to "lap" position, substantially as specified.

13. In an apparatus of the character described, a closed electric circuit, a normally active electrically controlled member and a normally inactive electrically controlled member, both in said circuit, a vehicle control mechanism common to both the normally active and normally inactive electrically controlled members, each of said electrically controlled members being adapted to independently effect the operation of the vehicle control mechanism by the deenergization of the normally active member or the action of the normally inactive member, and means by which the normally inactive member may be energized, at indeterminate points in the path of travel of the vehicle.

14. In a vehicle control mechanism, the combination with brake mechanism of an electrically operated member for effecting the operation of said brake mechanism, a source of electrical energy, a normally closed electrical circuit in which said electrically operated member is included, means in said circuit affording sufficient resistance to pre-

vent the operation of said electrically operated member under normal conditions of use, and means for nullifying the influence of said resistance means by the operation of 5 a distant vehicle whereby the operation of said brake operating member is effected.

15. In a vehicle control mechanism, the combination with brake mechanism of an electrically operated member for effecting 10 the operation of said brake mechanism, a source of electrical energy, a normally closed electrical circuit in which said electrically operated member is included, means in said circuit affording sufficient resistance to prevent 15 the operation of said electrically operated member under normal conditions of use, and a shunt circuit controlled by a distant vehicle adapted to pass current through the brake operating member independent of 20 the resistance means thereby effecting the operation of said member.

16. In a vehicle control mechanism, a brake, a brake control member, a control member for the motive power, means including 25 an electric circuit controlled by a distant vehicle for simultaneously operating both control members, and for subsequently reversing the brake control member independent of the control member of the motive 30 power.

17. In a vehicle control mechanism, the combination with brake mechanism of electrically operated member for effecting the operation of said brake mechanism, a source 35 of electrical energy, a normally closed electrical circuit in which said electrically operated member is included, means in said circuit affording sufficient resistance to prevent 40 the operation of said electrically operated member under normal conditions of use, and a shunt bridged across the said normally closed circuit by a distant vehicle adapted to nullify the effect of the said resistance means.

45. 18. In a vehicle control mechanism, the combination with brake mechanism of electrically operated means for effecting the operation of the brake, a source of electrical energy, a resistance means, a normally closed 50 circuit in which the resistance means and the operating means are connected in series with said source of electrical energy, said resistance being sufficient to prevent the operation of the operating means, and means 55 for closing said circuit through the brake operating means by the action of a distant vehicle and independent of the resistance means.

60. 19. In a vehicle control mechanism, a brake, a brake control member, a control member for the vehicle motive power, a normally closed electric circuit, and means for operating both control members and means for automatically reversing the brake control member independent of the motive 65

power control member upon the opening of the normally closed circuit.

20. In a mechanism of the character described, electrically operated vehicle control mechanism, a movable vehicle controlled thereby, a normally closed electric circuit, a shunt circuit, resistance in said shunt circuit regulated by the movement of the vehicle, means for closing the shunt circuit at a distant point outside the vehicle, said vehicle control mechanism being controlled by either of said circuits, whereby the opening of the normally closed circuit or the passage of current through the shunt circuit when the vehicle has approached within predetermined range of the distant circuit closing point will cause the operation of the vehicle control mechanism.

21. In a vehicle control mechanism, a movable vehicle, a control member for the vehicle motive power, a normally closed electric circuit, a shunt circuit, the resistance of which varies with the movement of the vehicle, means for closing the shunt circuit at a distant point outside the vehicle, means controlled by either of the circuits for operating the motive power control member, the construction and arrangement being such that the opening of the normally closed circuit or the passage of current through the shunt circuit will cause the operation of the motive power control member when the vehicle has approached within a prescribed range of the distant circuit closing point.

22. In a mechanism of the character described, a vehicle equipped with movable throttle control means and an air brake apparatus, the engineer's valve of which is movable to "running" "service" and "lap" positions, characterized by apparatus for automatically moving the throttle control means to "cut off" position and the engineer's valve of the air brake apparatus from "running" to "service" position and thence to "lap" position leaving the throttle in its "cut off" position, substantially as specified.

23. A vehicle control member, automatic actuating means therefor including, a driven member, continuously operating actuating means adapted to actuate the driven member to and fro normally inoperatively positioned in relation with the driven member, means for relatively shifting the driven member and actuating means into operative relation whereby said driven member will be initially operated first in one direction and then in the opposite direction, and means for automatically varying the interval of time between the initial operation and the retraction of the driven member.

24. A vehicle control member, automatic actuating means therefor including a driving and a driven member, said members being normally inoperatively positioned in relation one with the other, means for rela- 130

- tively moving said members into operative position and retracting means for the driven member operatively connected with the driven member by the operation of the 5 driven member.
25. In a vehicle control mechanism, a brake control member, a fluid pressure chamber the pressure of which is varied by the operation of the brake control member, and 10 means brought into operation by the variation of the chamber pressure for actuating the brake control member throughout a subsequent operation.
26. A vehicle control member, automatic 15 actuating means therefor including a driven member, an actuating member and a retracting member therefor, said members being normally inoperatively positioned, and electrically operated means for relatively moving 20 the actuating member and driven member into operative relation and fluid pressure means for thereafter relatively moving the driven member and retracting member into inoperative relation.
25. 27. A vehicle control member, automatic actuating means therefor including a mechanically operated driven member, a mechanically operated actuator therefor, electrical means controlling the interengagement 30 of the driven member and actuator, and means set in operation by the action of the driven member to effect the retraction of the driven member, substantially as specified.
28. In a vehicle control mechanism, a vehicle, a vehicle control member, fluid pressure means for operating the vehicle control member, a valve controlling the action of the fluid under pressure, a reciprocatory actuator for the valve normally reciprocating 40 in a plane removed therefrom, and means for automatically shifting the plane of reciprocation of the actuator into and out of operative relation with the valve at indeterminate points in the travel of the vehicle.
45. 29. In a mechanism of the character described, a vehicle control mechanism, fluid pressure means for operating said mechanism, a valve controlling the action of the fluid under pressure, a constantly reciprocating actuator for said valve and means controlled by the approach of a second vehicle 50 for operatively connecting the valve and actuator.
30. In a mechanism of the character described, a vehicle, a vehicle control mechanism, fluid pressure operated means for operating said mechanism, a valve controlling the fluid under pressure, a constantly operating actuator for said valve and means for 55 operatively connecting the valve and actuator when the vehicle exceeds a predetermined rate of speed but inoperative at other rates of speed.
31. In a mechanism of the character described, a vehicle, vehicle control mechanism, 60 fluid pressure means for operating the vehicle control mechanism, a valve controlling the action of the fluid under pressure, an actuator for said valve movable into and out of operative engagement therewith, 70 means for automatically connecting the actuator and valve for operative action, and means for automatically shifting the actuator out of engagement with the valve upon the operative movement of said valve, substantially as specified.
32. In a construction of the character described, a vehicle, vehicle control mechanism, fluid pressure means for operating the mechanism, a valve controlling the action of the fluid under pressure, actuating means for automatically alternating the movement of the valve and speed controlled means for governing the rate of alternation of the valve. 85
33. In a mechanism of the character described, a vehicle, vehicle control mechanism, fluid pressure means for operating said mechanism, a valve controlling the action of the fluid under pressure, means for automatically actuating said valve, and means governed by the speed of the vehicle for subsequently automatically retracting said valve. 90
34. In a construction of the character described, two relatively movable vehicles, a set of electrically controlled vehicle control mechanism for each vehicle, an intermediate electrical circuit common to both sets of vehicle control mechanism, means for intermittently bridging each set of control mechanism across said circuit, and circuit closing means associated with each vehicle adapted to intermittently close said circuit independent of said vehicle control mechanism, said control mechanism being operative upon the simultaneous bridging of the mechanism of one vehicle across the circuit and the operation of the circuit closing means of the other vehicle when said vehicles are 100 within prescribed range of each other. 105
35. In a vehicle control mechanism, a vehicle, a vehicle control member, fluid pressure means for operating the vehicle control member, a movable operator member controlling the action of the fluid under pressure, a reciprocatory push bar, a support therefor normally supporting the push bar in an inoperative position, and means for automatically shifting said support to permit the engagement of the push bar and operator member. 115
36. In a vehicle control mechanism, a vehicle, a vehicle control member, fluid pressure means for operating the vehicle control member, a movable operator member controlling the action of the fluid under pressure, a reciprocatory push bar, a movable support therefor, an electromagnet controlling the movement of the support, and means 120
- 125
- 130

for controlling the magnet from a distant point to permit the engagement of the push bar and operator member.

37. In a vehicle control mechanism, a vehicle, a vehicle control member, fluid pressure means for operating the vehicle control member, a movable operator member controlling the action of the fluid under pressure, a reciprocatory push bar, a movable support upon which the push bar is supported, an electromagnet, a pivoted armature therefor, a connection between the pivoted armature and the movable support, and means to energize the magnet controlled from a distant point.

38. The combination with vehicle control mechanism, of a speed controlled member, an electric circuit including a plurality of spaced contacts, a circuit closer regulated by said speed controlled member whereby it will be engaged with different contacts at different rates of speed, a plurality of ramps one related to each contact, an electric circuit closer operated by each ramp, the simultaneous closing of the circuit under the influence of a ramp and the engagement of the speed controlled circuit closer with the particular contact related to said ramp effecting the operation of said control mechanism and means for automatically varying the duration of the period of operation of the control mechanism in unison with the speed of the vehicle.

39. In a vehicle control mechanism, a brake, a brake control member, fluid pressure means for operating the brake control member, a movable operator member controlling the action of the fluid under pressure, automatic means for initially operating the operator member, and means for subsequently retracting the operator member, and means for regulating the interval of time intervening between the initial operation and retraction of the operator member.

40. In a vehicle control mechanism, a vehicle, a vehicle control member, fluid pressure means for operating the vehicle control member, a movable operator member controlling the action of the fluid under pressure, an actuating member therefor, an offset portion on one of the members, a movable hook on the other member adapted to engage the said offset portion to interlock the operator and the actuator members, and means for normally holding the hook in retracted position and means operating independent of the position of the vehicle in its path of travel for releasing said hook.

41. In a vehicle control mechanism, a brake, a brake control member, fluid pressure means for operating the brake control member, a movable operator member for controlling the action of the fluid under pressure, a hook shaped actuator bar, a hook

plate pivoted upon the operator member, a spring tending to project the engaging portion of the hook plate into the path of the actuator member, and means for normally holding the hook plate in retracted position against the tension of its spring.

42. In a vehicle control mechanism, a brake, a brake control member, fluid pressure means for operating the brake control member, a movable operator member controlling the action of the fluid under pressure, a hook shaped actuator bar, a hook plate pivoted upon the operator member, a spring tending to project the engaging portion of the hook plate into the path of the actuator member, a movable stop limiting the movement of the hook plate and means for withdrawing the stop operated from a distant point outside the vehicle.

43. In a vehicle control mechanism, a brake, a brake control member, fluid pressure means for operating the brake control member, a movable operator member controlling the action of the fluid under pressure, an actuator member therefor, an engager cam carried by one of the said members and tending to project into the path of the other member, a stop normally holding the engager in inoperative position, and means for automatically withdrawing the stop to permit the interengagement of the operator and actuator members.

44. In a vehicle control mechanism, a brake, a brake control member, fluid pressure means for operating the brake control member, a movable operator member controlling the action of the fluid under pressure, an actuator member therefor, an engager cam carried by one of the said members and tending to project into the path of the other member, a stop normally holding the engager in inoperative position, an electric circuit controlled from a distant point outside the vehicle, and electrically operated means controlled thereby for withdrawing the stop.

45. In a mechanism of the character described, a vehicle, vehicle control mechanism, fluid pressure means for operating said control mechanism, contact members located in the path of travel of the vehicle, engaging means upon the vehicle coacting with said contact members to effect the operation of the fluid pressure means, and speed controlled means for determining the duration of the period of operation of said fluid pressure means.

46. In a vehicle control mechanism, a brake, a brake control member, fluid pressure means for operating the brake control member, a movable operator member controlling the action of the fluid under pressure, means for actuating the operator mem-

- ber, a retractor therefor and fluid pressure means for controlling the interengagement of the retractor and operator set in operation by the initial movement of the operator.
- 5 47. In a vehicle control mechanism, a 70
brake, a brake control member, fluid pressure means for operating the brake control member, a movable operator member controlling the action of the fluid under pressure, an actuator therefor, a fluid pressure chamber, means for controlling the engagement of the actuator and operator member by the variations of fluid pressure in said pressure chamber, and means for automatically varying the fluid pressure.
- 10 48. In a vehicle control mechanism, a 75
brake, a brake control member, fluid pressure means for operating the brake control member, a movable operator member controlling the action of the fluid under pressure, an actuator therefor, a cylinder, a piston therein, an operative connection between the piston and actuator by which the actuator is moved into and out of operative position, and means for varying the fluid pressure within the cylinder.
- 15 49. In a vehicle control mechanism, a 80
brake, a brake control member, fluid pressure means for operating the brake control member, a movable operator member controlling the action of the fluid under pressure, an actuator therefor movable into and out of operative position, a spring tending to move the actuator in one direction, fluid 85 pressure means tending to move the actuator in the opposite direction, and means for varying the fluid pressure by the operation of the brake control member.
- 20 50. In a vehicle control mechanism, a 90
brake, a brake control member, fluid pressure means for operating the brake control member, a movable operator member for controlling the action or the fluid under pressure, an actuator for said operator member, fluid pressure means controlled by the operation of the brake for controlling the movement of the actuator.
- 25 51. In a vehicle control mechanism, a 95
brake, a brake control member, fluid pressure means for operating the brake control member, a movable operator member for controlling the action of the fluid under pressure, a pushing actuator, means for operatively engaging the pushing actuator and operator, a retracting actuator, and means for operatively engaging the retracting actuator and operator subsequent to each operation of the pushing actuator.
- 30 52. In a vehicle control mechanism, a 100
brake, a brake control member, fluid pressure means for operating the brake control member, a movable operator member controlling the action of the fluid under pressure, an actuator member normally held out of operative position by fluid pressure, and means for varying the fluid pressure to permit the operative engagement of the actuator and operator members.
- 35 53. In a vehicle control mechanism, a 105
brake, a brake control member, fluid pressure means for operating the brake control member, a movable operator member controlling the action of the fluid under pressure, an operating actuator and a retracting actuator, electrically controlled 110 means for operatively engaging the operating actuator and operator member, and fluid pressure means controlled by the operation of the operating actuator for operatively engaging the retracting actuator and operator members.
- 40 54. In a vehicle control mechanism, a 115
brake, a brake control member, fluid pressure means for operating the brake control member, a movable operator member for controlling the action of the fluid under pressure, an operating actuator and a retracting actuator, electrically controlled means for operatively engaging the operating actuator and operator member, and fluid pressure means controlled by the operation of the operating actuator for operatively engaging the retracting actuator and the operator member.
- 45 55. In a vehicle control mechanism, a 120
brake, a brake control member, fluid pressure means for operating the brake control member, a movable operator member for controlling the action of the fluid under pressure, a movable head controlling the opera- 125
- 50 56. In a vehicle control mechanism, a 125
brake, a brake control member, fluid pressure means for operating the brake control member, a movable operator member for controlling the action of the fluid under pressure, a movable head controlling the opera- 130

- tor member, a fluid pressure chamber, a piston therein connected with the movable head, and means for varying the fluid pressure within the chamber. 65
- 5 59. In a vehicle control mechanism, a 70
brake, a brake control member, fluid pressure means for operating the brake control member, a movable operator member for controlling the action of the fluid under 75
10 pressure, a movable head controlling the operator member, a spring tending to reciprocate the head, and a fluid pressure means for regulating the movement of the head under the influence of the spring. 80
- 15 60. The combination with a vehicle control mechanism of a movable control member therefor adjustable to different relative positions, means for automatically adjusting said control member to an initial operative 85
20 position and subsequently to a second operative position, and speed controlled means for varying the interval of time between the adjustment of said member to its initial and second positions. 90
- 25 61. In a vehicle control mechanism, a 95
brake, a brake control member, fluid pressure means for operating the brake control member, an operator controlling the action of the fluid under pressure, a retractor for effecting the return of the brake control member, controlled by the operation of the brake, a speed governor means controlled thereby for the interval intervening between the operation of the brake and the retractor. 100
- 30 62. In a vehicle control mechanism, a 105
brake, a brake operating mechanism, means for automatically retracting the brake subsequent to the application thereof, a speed governor and means controlled thereby for determining the extent of the intervening 110
40 interval of time between the application of the brake and its retraction. 115
63. In an apparatus of the character described, the combination, with a fluid pressure 120

moving said member in one direction and subsequently automatically retracting said member, and speed controlled means for automatically regulating the interval of time intervening between the operation and retraction of said member.

73. In an apparatus of the character described, the combination with a vehicle control mechanism of a normally closed electric circuit, a normally active and a normally inactive electrically controlled member in said circuit both said members being normally ineffective to cause the operation of said vehicle control mechanism, means to effect the operation of said mechanism by the action of the normally active member upon the opening of the circuit, a shunt circuit bridged across the main circuit, and means to effect the operation of said mechanism by the action of the inactive member upon the circulation of current through the shunt circuit.

74. In a vehicle control mechanism, a brake, operating mechanism therefor, a control member for the vehicle motive power, locking means for the brake operating mechanism, and means for releasing the brake locking mechanism by the operation of the motive power control member.

75. In a vehicle control mechanism, a brake, a brake operating mechanism, a control member for the vehicle motive power, restoring devices for the brake operating mechanism, a detent holding the restoring devices in operated position and means to release the restoring devices by the operation of the motive power control member.

76. In a vehicle control mechanism, a brake, a brake operating mechanism, a control member for the vehicle motive power, a movable member cooperating with the brake operating mechanism, a detent engaging the movable member to retain it in operated position, and a connection between the detent and the motive power control member.

77. In a vehicle control mechanism, a brake, a brake operating mechanism, a control member for the vehicle motive power,

a detent adapted to retain the brake operating mechanism in a predetermined position, and a connection between the detent and motive power control member by which the detent is disengaged upon the operation of the said control member from neutral position.

78. In a vehicle control mechanism, a brake, a brake operating mechanism, an electromagnet, a movable armature for said magnet adapted by its movement to cause the operation of the brake mechanism, a manually operated detent for said armature adapted to support the armature within the zone of influence of the magnet, said detent being released by the subsequent attraction of the armature by the magnet.

79. In a vehicle control mechanism, a brake, a brake operating mechanism including a pivoted lever, an armature carried by the lever, an electromagnet tending to attract the armature, a detent adapted to support the armature within the zone of influence of the magnet, said detent being released by the attraction of the armature, and connections between the lever and brake operating mechanism causing an application of the brake upon the subsequent release of the armature by the magnet.

80. In a vehicle control mechanism, a brake, a brake operating mechanism, an electric circuit controlling the brake operating mechanism, a normally open contact in said circuit, means for closing said contact at a predetermined point in the path of travel of the vehicle, a second contact in the same circuit, a speed governor and means controlled thereby for closing the second contact, the construction being such that the brake mechanism will be operated by the closing of both contacts.

In testimony whereof I have hereunto set my hand this 10th day of September A. D. 1914.

HARRY G. DAVIS.
